UNITED STATES PATENT OFFICE.

GEORGE S. THOMPSON, OF HOCKESSIN, DELAWARE.

STAY-BOLT.

No. 823,825.

Specification of Letters Patent.

Patented June 19, 1906.

Application filed October 7, 1905. Serial No. 281,841.

To all whom it may concern:

Be it known that I, GEORGE S. THOMPSON, a citizen of the United States, residing at Hockessin, Newcastle county, and State of Delaware, have invented certain new and useful Improvements in Stay-Bolts, of which the following is a specification.

My invention relates to the form and construction of articulated stay-bolts, especially those of the character disclosed in Letters Patent No. 792,863, issued to me June 20, 1905, the present invention being designed to embody in a three-part stay-bolt the principles and advantages therein set forth in connection with a two-part stay-bolt. As in the latter case, while my articulated bolt is applicable for various other uses, it is intended particularly for use in steam-generators, especially locomotives, between the outer shell and the fire-box shell.

The main object is to attain a three-part articulated stay-bolt which while capable of lateral flexure by reason of its joints shall at the same time be practically unyielding axially or longitudinally, so as to hold the boiler and fire-box firmly and rigidly in position with relation to each other, all looseness or play lengthwise of the bolt being obviated by the peculiar construction of the joints between the parts, as hereinafter more fully described.

As in my patent hereinbefore referred to, I attain a maximum of strength for a given size and thickness of bolt and prolong its life and usefulness by relieving the weaker parts of all excessive pressure and distributing and neutralizing the strain, both of tension and compression on the parts generally, both during manufacture, application, and use. I also herein aim to preserve the flexibility of the stay-bolt as a whole by preventing the accumulation or lodgment of sediment between the articulated parts or joints, thus obviating lateral strain that might otherwise result from impaired flexibility.

Another feature of my present invention is designed to afford prompt evidence of any break or fracture from any cause occurring at the weaker part of the stay-bolt, which is adjacent to its connection with the fire-box plate, not because this bolt is weakened in any particular, but because the other or outer end of the bolt, which was formerly the weaker end, has been materially strengthened.

A distinguishing feature of my present in-

vention consists in the use of a central coupling-link made in one piece without joint or weld, which I accomplish by forming the loops of both the eyebolt and the eye-head of straps which are passed through the link and then bent over and welded to central fillers, the welded portions being then shaped and threaded for engagement with the boiler and fire-box plates.

An advantage of my construction of three-part stay-bolt is that both eyebolt and eye-head may be screwed home simultaneously in the plates to which they are applied, the bolt as a whole being particularly rigid and as of one piece when supported and driven longitudinally, since there is no looseness between the parts, the articulating bearing-surfaces being locked in intimate contact with each other, also preventing the independent rotation of either part upon the other. In this connection a feature of my invention consists in forming the eyebolt with a nose of less diameter than the threaded portion of the eyebolt to facilitate the entrance and connection of the male screw-thread on the eyebolt with the female screw-thread formed for its reception in the fire-box plate.

The severest strain to which the bolt is subjected being that of compression by reason of the unequal expansion of the plates to which it is attached, since the fire-box plate is exposed to a higher temperature than the boiler-shell, I so arrange and construct my parts that the force of compression is met and expended upon the external surface of the coupling-link, the eyes of which are protected by central depressions in the opposed concentric bearing-surface of the eye-head and eyebolt, so that the pressure is transmitted to and through the longitudinal sides of the link, as hereinafter shown.

My invention also includes certain other features in the construction and arrangement of parts hereinafter described and claimed specifically.

In the accompanying drawings, Figure 1 is an elevation of my improved articulated stay-bolt applied to and between a boiler-shell and a furnace-plate. Fig. 2 is an elevation of the bolt before application, the view being taken at right angles to Fig. 1. Fig. 3 is a side elevation of the filler used in the formation of the eye-head; Fig. 4, an edge view of the same at right angles to Fig. 3. Fig. 5 is a face end view of the filler. Fig. 6 is a rear view of the filler. Fig. 7 is a section

taken upon plane of line 7 7, Fig. 3: Fig. 8 is a side elevation of the coupling-link; Fig. 9, an edge view of the coupling-link. Fig. 10 is a central longitudinal section upon plane 5 of line 10 10, Fig. 2; Fig. 11, a similar section of the whole bolt, taken upon plane of line 11 11; Fig. 10. Fig. 12 is a detail view illustrating the construction of the eyebolt. Fig. 13 is a similar view illustrating the construction 10 of the eye-head. Fig. 14 is a transverse section taken upon plane of line 14 14, Fig. 13. Fig. 15 is a section taken upon the same plane after the sides of the strap have been compressed.

15 My improved articulated stay-bolt consists of a central coupling-link C, an eye-head H, and an eyebolt B. The coupling-link is formed preferably of a single piece of metal either cast or drop-forged without weld or joint. I thus attain a coupling of uniform 20 texture and strength, which latter is further enhanced by forming the link with a broad central web c, from which the body of the link tapers in either direction to merge into 25 the knuckles c' c', which are circular in cross-section, as will be seen more particularly by reference to Fig. 11. The eyes c² c² are formed with concave seats c³ c³ of the same radius as that of the knuckles h² on the eye- 30 head H and the knuckles b on the eyebolt B, both of which knuckles are circular in cross-section, as will be seen by reference to Fig. 10. Back of the seats c³ c³ the eyes are enlarged to form eccentric spaces c⁴ c⁴ for the 35 purpose not only of facilitating the insertion of the cylindrical strap-rods for the eyebolt B and eye-head H during the manufacture of the bolt, but also for a more important purpose—that of avoiding contact between the 40 internal surfaces of the eyes and the external convex surfaces of the loops of the eyebolt and stay-bolt, as will be seen by reference to Figs. 1, 10, and 11 of the drawings, and also for the purpose of avoiding the lodgment of 45 sediment, as hereinafter set forth.

The eyebolt is constructed in substantially the same manner as set forth in my Letters Patent hereinbefore referred to, the only difference being that in the present case the eyebolt B is formed with an extension or nose b' 50 beyond the threaded portion b² of the shank and is also formed with an internal recess or bore b³, extending from the end of the nose b' preferably through and beyond the said threaded portion b² of the eyebolt, as will be seen by reference to Figs. 10 and 11—that is to say, in the formation of the eyebolt B a cylindrical rod b⁴ is passed through one of the eyes c² of the coupling-link C and bent over 55 to form the loop of the eyebolt, a central filler b⁵ being then inserted between the ends of the rod, which ends are then flattened and welded to the filler, after which the welded portions of the eyebolt are shaped and threaded, as shown, by well-known means.

As heretofore, the inner end of the filler b⁵ is formed with concave bearing-surfaces b⁶ b⁶, with a central depression b⁵⁵ between them, the said concave bearing-surfaces b⁶ b⁶ being concentric with the knuckles b, the inner convex surface of which fits in the opposed concave seat c' in the coupling-link C, as clearly shown in Fig. 10, by reference to which it will also be seen that the concave bearing-surfaces b⁶ b⁶ of the eyebolt engage with the 70 opposed concentric convex surface c⁵ of the link-knuckle. Thus the articulation of the parts is provided for without looseness or longitudinal play, the knuckles fitting each other snugly and being held to their respective seats by the concave bearing-surfaces b⁶ b⁶, which, however, do not interfere with the pivotal or lateral flexure of the parts upon 75 each other within ample limits.

The nose b' of the eyebolt B is reduced in 80 diameter to less than that of the threaded portion b² of the eyebolt and is preferably tapered toward the end also to facilitate its introduction into the tapped hole in the firebox plate F, the nose thus acting as a guide 85 and centralizer for the threaded portion b² of the shank, so that the engagement between the male and female screw-threads is easily effected during the operation of applying the stay-bolt as a whole to and between the 90 boiler-shell S and the fire-box plate F. When thus applied, the telltale-bore b⁸ opens into the fire-chamber and in case of the rupture of the threaded shank admits water or steam 95 from the space between the shell S and plate F to the fire-box, thereby directing attention to the defect. I thus protect the eyebolt, because it is necessarily the weaker part of the 100 bolt, relatively speaking, not because it has been weakened, but because the other parts 105 of the stay-bolt, the coupling-link C, and the eye-head H have been materially strengthened by my structure of stay-bolt, and also because the stay-bolt is necessarily subjected to the greatest degree of strain or compression 110 at its junction with the fire-box plate owing to the high degree of temperature, and hence to the extremes of expansion and contraction to which the plate is subjected. The eye-head H is likewise formed from a central 115 filler h and a strap h', consisting of a cylindrical rod, the rod being bent to form the knuckle h² and the filler h being inserted between the ends of the rod, which are then flattened and welded to the filler, the welded 120 portions being then shaped externally. In order to afford the required thickness of metal to form the head h'', the filler is made with lateral extensions in which are formed recesses h²² h²² for the reception of the ends of 125 the strap h'.

The finished head h'' is preferably in the form of a conic frustum peripherally threaded for engagement with a hole tapped for its 130 reception in the boiler-shell S, and the base of

this conic section is formed with an extension h^{33} , which is polygonal in cross-section or otherwise so formed as to provide for the simultaneous rotation of the eye-head and link C and eyebolt B upon their common longitudinal axes, for which purpose various well-known mechanical expedients may be resorted to if the polygonal extension h^{33} is not desired.

- 10 The inner end or face of the filler is formed with the concave bearing-surfaces h^{44} h^{44} with a central depression or space h^{55} between them, said concave bearing-surfaces h^{44} h^{44} being concentric to the knuckle h^2 and bearing against the opposed convex concentric surface c^5 of the coupling-link, as will be seen by reference to Fig. 10. Thus, as in the case of the articulation of the eyebolt B, the parts are held in intimate engagement with each 15 other and no longitudinal looseness or play is possible in either direction, the stay-bolt being maintained at a prescribed length when 20 the parts are extended with their longitudinal axes in alinement, so that considered axially the stay-bolt is practically unyielding and rigid in the transmission of longitudinal strain or compression, while flexible transversely to adapt the parts to lateral strain. In this connection the coupling-link C is of 25 special importance, since it readily adapts itself to and compensates for any lack of perfect axial alinement from any cause between the eye-head H and the eyebolt B.

The recesses or depressions h^{55} and b^{55} in 30 the inner faces of the eye-head H and eyebolt B, respectively, are of importance in that they relieve the central portions of the knuckles $c' c'$ of the coupling-link from compression, transferring the pressure to the sides of 35 the link, where it can do no possible harm.

The eccentric extensions c^3 c^3 of the eyes c^2 c^2 of the coupling-link C not only obviate contact with the convex external surfaces of the eye-head H and eyebolt B, thereby protecting 40 the knuckles of said parts against the force of compression during use, but they also perform another important function in that they protect the knuckles against injury during the upsetting of the metal in the manufacture of the bolt, and thereby preserve smooth even peripheral surfaces upon which sediment can find no resting-place, the collection of sediment between the joints having a tendency to impair the usefulness and 45 strength of the stay-bolt.

By my construction of eye-head the outer end of the stay-bolt is rendered much more substantial and durable than heretofore, the setting of the fiber of the metallic strap by 50 compression, so that resilience and stretch is eliminated, &c., as set forth in my said Letters Patent in connection with the description of the formation of my special form of eyebolt, being advantages inherent in the 55 present structure of both eye-head and eye-

bolt, so that they do not need to be recapitulated herein.

No claim is made in this application to the method of making the bolt herein described, as the same forms the subject-matter of my 70 divisional application, Serial No. 210,002, filed April 3, 1906.

What I claim as my invention, and desire to secure by Letters Patent, is—

1. An articulated stay-bolt having an eye-head consisting of a central filler the inner edge of which is formed with a concave bearing-surface concentric to the opposed inner surface of the eye-loop for engagement with the concentric surface of the part to which the 75 eyebolt is coupled, and a strap formed of a cylindrical rod looped into the eye of the part to which the eye-head is coupled, said cylindrical rod being bent to form the eye of the head, and having its ends welded to the filler 80 on opposite sides thereof, for the purpose described.

2. An articulated stay-bolt having an eye-head consisting of a central filler the inner edge of which is formed with concave bearing- 85 surfaces with a depression between them, said concave bearing-surfaces being concentric to the opposed inner surface of the eye-loop or knuckle for engagement with the concentric surface of the part to which the 90 eyebolt is coupled, and a strap formed of a cylindrical rod looped into the eye of the part to which the eye-head is coupled, said cylindrical rod being bent to form the eye of the head and having its ends welded to the filler 95 on opposite sides thereof, for the purpose described.

3. An articulated stay-bolt having an eye-head consisting of a central filler the inner edge of which is formed with a concave bearing- 100 surface concentric to the opposed inner surface of the eye-loop for engagement with the concentric surface of the part to which the eyebolt is coupled, and a strap formed of a cylindrical rod looped into the eye of the part to which the eye-head is coupled, said cylindrical rod being bent to form the eye of the head and having its ends welded to the 105 filler on opposite sides thereof, the welded portions being shaped into a peripherally-threaded conic frustum, for the purpose described.

4. An articulated stay-bolt having an eye-head consisting of a central filler the inner edge of which is formed with concave bearing- 110 surfaces with a depression between them, said concave bearing-surfaces being concentric to the opposed inner surface of the eye-loop for engagement with the concentric surfaces of the part to which the eyebolt is 115 coupled, and a strap formed of a cylindrical rod looped into the eye of the part to which the eye-head is coupled, said cylindrical rod being bent to form the eye of the head and having its ends welded to the 120 filler on opposite sides thereof.

5. An articulated stay-bolt having an eye-head consisting of a central filler the inner edge of which is formed with concave bearing- 125 surfaces with a depression between them, said concave bearing-surfaces being concentric to the opposed inner surface of the eye-loop for engagement with the concentric surfaces of the part to which the eyebolt is 130 coupled, and a strap formed of a cylindrical rod looped into the eye of the part to which the eye-head is coupled, said cylindrical rod being bent to form the eye of the head and having its ends welded to the filler on oppo-

site sides thereof, the welded portions being shaped into a peripherally-threaded conic frustum, for the purpose described.

5. An articulated stay-bolt having an eye-head consisting of a central filler having recessed sides and an inner edge formed with a concave bearing-surface concentric to the opposed inner surface of the eye-loop for engagement with the concentric surface of the part to which the eyebolt is coupled, and a strap formed of a cylindrical rod looped into the eye of the part to which the eye-head is coupled, said cylindrical rod being bent to form the eye of the head and having its ends fitting in the recessed sides of the filler and welded thereto, for the purpose described.

6. An articulated stay-bolt having an eye-head consisting of a central filler having recessed sides and an inner edge formed with 20 concave bearing-surfaces with a depression between them, said concave bearing-surfaces being concentric to the opposed inner surface of the eye-loop for engagement with the concentric surface of the part to which the eye-bolt is coupled, and a strap formed of a cylindrical rod looped into the eye of the part to which the eye-head is coupled, said cylindrical rod being bent to form the eye of the head, and having its end fitting in the recessed sides of the filler and welded thereto, for the purpose described.

7. An articulated stay-bolt having an eye consisting of a central filler having recessed sides and an inner edge formed with a concave bearing-surface concentric to the opposed inner surface of the eye-loop for engagement with the concentric surface of the part to which the eyebolt is coupled, and a strap formed of a cylindrical rod looped into 35 the eye of the part to which the eye-head is coupled, said cylindrical rod being bent to form the eye of the head and having its ends fitting in the recessed sides of the filler and welded thereto, the welded portions being 40 shaped into a peripherally-threaded conic frustum for the purpose described.

8. An articulated stay-bolt having an eye-head consisting of a central filler having recessed sides and an inner edge formed with 50 concave bearing-surfaces with a depression between them, said concave bearing-surfaces being concentric to the opposed inner surface of the eye-loop for engagement with the concentric surface of the part to which the eyebolt is coupled, and a strap formed of a cylindrical rod looped into the eye of the part to which the eye-head is coupled, said cylindrical rod being bent to form the eye of the head and having its ends fitting in the recessed sides 55 of the filler and welded thereto, the welded portions being shaped into a peripherally-threaded conic frustum for the purpose described.

9. An articulated stay-bolt having an eye-head formed with a body in the shape of a

peripherally-threaded conic frustum with an eye-loop the inner surfaces of which are concentric, a link of less width than the threaded portion of the eye-head, said link being formed with concentric surfaces for engagement with the concentric inner surfaces of the loop in the eye-head, and an eyebolt of less diameter than the eye-head and coupled to the latter by said link, for the purpose described. 70

10. An articulated stay-bolt having an eye-head formed with a body portion in the shape of a peripherally-threaded conic frustum with an eye-loop the inner surfaces of which are concentric, a link of less width than the threaded portion of the eye-head formed with concentric surfaces for engagement with the concentric inner surfaces of the loop in the eye-head, and also formed with concentric surfaces for engagement with the corresponding concentric inner surfaces of the loop of an eyebolt, and said eyebolt also of less diameter than the threaded portion of the eye-head, and formed with a loop having inner concentric surfaces for engagement with the link, for the purpose described. 75

11. An articulated stay-bolt having an eye-head formed with a body portion in the shape of a peripherally-threaded conic frustum with an eye-loop the inner surfaces of which are concentric, a link of less width than the threaded portion of the eye-head formed with concentric surfaces for engagement with the concentric inner surfaces of the loop in the eye-head, and also formed with concentric surfaces for engagement with the corresponding concentric surfaces of the loop of an eyebolt, and said eyebolt also of less diameter than the threaded portion of the eye-head and formed with a loop having inner concentric surfaces for engagement with the link, said link being also formed with a central web between its eyes for the purpose described. 90

12. An articulated stay-bolt having an eye-head formed with a body portion in the shape of a peripherally-threaded conic frustum with an eye-loop the inner surfaces of which are concentric, a link of less width than the threaded portion of the eye-head, formed with concentric surfaces for engagement with the concentric inner surfaces of the loop in the eye-head, and also formed with concentric surfaces for engagement with the corresponding concentric inner surfaces of the loop of an eyebolt, and said eyebolt also of less diameter than the threaded portion of the eye-head and formed with a loop having inner concentric surfaces for engagement with the link, said link being also formed with a central web between its eyes of greater width than the ends of the link, for the purpose described. 110

13. An articulated stay-bolt having an eye-head formed with a body portion in the shape of a peripherally-threaded conic frustum 125

- with an eye-loop the inner surfaces of which are concentric, a link of less width than the threaded portion of the eye-head, formed with concentric surfaces for engagement with the concentric inner surfaces of the loop in the eye-head, and also formed with concentric surfaces for engagement with the corresponding concentric inner surfaces of the loop of an eyebolt, and said eyebolt also of less diameter than the threaded portion of the eye-head and formed with a loop having inner concentric surfaces for engagement with the link, the eyes in the said link being formed with semicircular seats of the same diameter as the engaging portions of the loops of the eye-head and eyebolt respectively, and with spaces back of said semicircular seats of greater diameter than that of the seats for the purpose described.
14. An articulated stay-bolt having an eye-head formed with a body portion in the shape of a peripherally-threaded conic frustum with an eye-loop the inner surfaces of which are concentric, a link of less width than the threaded portion of the eye-head, formed with concentric surfaces for engagement with the concentric inner surfaces of the loop in the eye-head, and also formed with concentric surfaces for engagement with corresponding concentric inner surfaces of the loop of an eyebolt, and said eyebolt also of less diameter than the threaded portion of the eye-head and formed with a loop having inner concentric surfaces for engagement with the link, said link being formed in one piece without joint or weld, and the loops of the eyebolt and of the eye-head being formed of cylindrical rods which are passed through the eyes in the link and then bent and welded to fillers, for the purpose described.
15. An articulated stay-bolt consisting of an eye-head the body of which is in the form of a conical frustum threaded peripherally, a screw-eyebolt, and a link coupling the screw-eyebolt to the eye-head, the joints between the parts being formed to allow of pivotal or lateral play only, so that the parts are sustained against longitudinal movement upon or with relation to each other, for the purpose described.
16. An articulated stay-bolt consisting of an eye-head the body of which is in the form of a conical frustum threaded peripherally, a threaded eyebolt, and a link coupling the said threaded eyebolt to the said eye-head, the eyebolt and the coupling-link being both of less width than the eye-head, and the joints between the parts being formed to allow of pivotal or lateral play only so as to sustain the parts against longitudinal movement upon or with relation to each other, for the purpose described.
17. An articulated stay-bolt formed with a threaded eyebolt having a nose of less diameter than the threaded portion of the bolt for the purpose described.

18. The combination with boiler and furnace plates formed with opposed and coinciding screw-holes, of an articulated stay-bolt having an eye-head formed with a body portion in the shape of a peripherally-threaded conic frustum, and a threaded eyebolt coupled to the eye-head by a link having eyes which closely fit the loops of both the eye-head and the eyebolt so as to admit of pivotal or lateral flexure while preventing longitudinal movement between the parts, for the purpose described.
19. The combination with boiler and furnace plates formed with opposed and coinciding screw-holes, of an articulated stay-bolt having an eye-head formed with a body portion in the shape of a peripherally-threaded conic frustum, and a threaded eyebolt coupled to the eye-head by a link having eyes which closely fit the loops of both the eye-head and the eyebolt, so as to admit of pivotal lateral flexure while preventing longitudinal movement between the parts, said eyebolt being formed with a nose of less diameter than its threaded portion for the purpose set forth.
20. The combination with boiler and furnace plates formed with opposed and coinciding screw-holes, of an articulated stay-bolt having an eye-head formed with a body portion in the shape of a conic frustum threaded externally for engagement with the outer or boiler plate, and an eyebolt threaded for engagement with the plate of the fire-box, the eyebolt and the eye-head being coupled together by a link having eyes which closely fit the loops of both the eye-head and the eyebolt, so as to admit of pivotal or lateral flexure while preventing longitudinal movement between the parts, said eyebolt being formed with a telltale-bore opening into the fire-box, for the purpose described.
21. A three-part articulated stay-bolt consisting of two threaded eyepieces coupled together by a link formed of one solid piece without joint or weld with a central web of greater thickness than the other parts of the link, for the purpose described.
22. A three-part articulated stay-bolt consisting of two threaded eyepieces coupled together by a link, the link being formed with concentric bearing-surfaces at each end, and each eyepiece being formed with concentric bearing-surfaces which engage directly with those of the link so as to permit of pivotal flexure between the parts only, for the purpose described.
23. A three-part articulated stay-bolt consisting of two threaded eyepieces coupled together by a link, the link being formed with oblong eyes and with concentric bearing-surfaces at each end, and each eyepiece being formed with concentric surfaces which en-

gage directly with those of the link so as to permit of pivotal flexure between the parts only, for the purpose described.

24. A three-part stay-bolt consisting of an eye-head and an eyebolt each formed with an internal convex semicircular seat in its eye and with an internal concave bearing-surface concentric to said convex seat, and a coupling-link interposed between the said eye-head and said eyebolt and formed with concentric bearing-surfaces which engage with said concentric surfaces on the eye-head and eyebolt, for the purpose described.

25. A three-part stay-bolt consisting of an eye-head and eyebolt each formed with an

internal convex semicircular seat in its eye and with an internal concave bearing-surface concentric to said convex seat, and a coupling-link interposed between the said eye-head and said eyebolt and formed with concentric bearing-surfaces which engage with said concentric surfaces on the eye-head and eyebolt, and with elongated eyes which create a space between the link and the external surfaces of the said eye-head and eyebolt, for the purpose described.
